UNITED STATES PATENT OFFICE.

WARREN R. BRIGGS, OF STRATFORD, CONNECTICUT.

PENCIL SHARPENER AND WIPER.

Application filed January 26, 1926. Serial No. 33,783.

To all whom it may concern:

Be it known that I, WARREN R. BRIGGS, a citizen of the United States, residing at the town of Stratford, in the county of Fairfield and State of Connecticut, have invented certain new and useful Improvements in Pencil Sharpeners and Wipers; and I do declare the following to be a full, clear, and exact description of the invention, such as will enable others skilled in the art to which it appertains to make and use the same.

This invention relates to pencil sharpeners, but more particularly has reference to devices of this nature which are used to point or sharpen the lead element of a pencil by attrition along a suitable abrasive surface such as is readily provided by sandpaper.

Also the invention contemplates the provision of wipers within which the pencil point after sharpening may be cleansed of the dust caused by the sharpening so that such dust cannot fall on a drawing or other surface whose cleanliness is desired.

The invention is in the form of a low structure that is utilized on both sides and which is not at all likely to be upset and which rests on a table or drawing board convenient of access and readily shiftable to any desired location.

The accompanying drawings illustrate an approved embodiment of the invention and are to be read in connection with the description that follows, and similar numerals of reference denote like parts in the several figures of the drawing in which latter

Figure 1 is a plan view of a pencil sharpener constructed in accordance with this invention—

Figure 2 is a side elevation—

Figure 3 is a section at the line 3—3 of Figure 1, and

Figure 4 is a perspective view showing one end of the sharpener properly assembled while the other end is shown in position preparatory to assembly, the sand paper being omitted.

1 is an elongated support, preferably a metal plate, having at its opposite ends lugs 2 and at each of its lateral terminals a pair of ears 3 that are bent in opposite directions at right angles to said plate to form legs for the purpose hereinafter to be explained.

4 are two cylindrical shaped spring members made of thin spring metal and of a

width about equal to that of said plate, the biting edges of said members facing each other and embracing opposite ends of said plate, the lugs 2 extending through openings 5 in the outer walls of said member and bent, as shown at Figures 2 and 3, to secure the plate to these members.

On opposite sides of these openings 5 are slots 6, and clamps 7 extending throughout the width of the plate are positioned on opposite sides of the plate at each end, between the plate and the biting edges of the spring members 4, these clamps having pinch levers 8 which diverge from the outer ends of the clamps and extend through the slots 6.

Normally the resiliency of the spring members will bind these clamps firmly against the opposite faces of the plate with the levers 8 diverging, but when these levers are pinched together the clamps will be forced away from the plate against the resiliency of the spring members, as is shown at Figure 4 in the instance of the clamping structure that is ready for assembly.

9 are the wipers, preferably made of felt or heavy fabric that is doubled, the closed end of each wiper being confined between an edge of the spring member and the outer face of a clamp, the free edges of the wipers diverging and extending beyond the edges of the clamps, as clearly shown.

Strips 10 of sandpaper cut to suitable proportions are placed in position on the opposite faces of the plate by pinching the levers 8 and inserting the ends of said strips successively between the clamps and plate, the release of the levers causing these strips to be securely held in place.

It will be noted that the wipers are not disturbed by the removal or insertion of these strips, since said wipers are confined between the edges of the springs and the top faces of the clamps, whereas the strips are in contact with the plate and the bottom faces of the clamps.

In assembling the parts of the device the clamps are first positioned between the edges of the springs, the jaws of the springs then forced away from the clamps, and the wipers inserted between said edges and the clamps. Thereafter, the levers 8 are pinched together, as shown at Figure 4, and the lugs inserted through the openings 5 and bent down.

While it is preferred to form the ears 3 to provide legs, and to possibly present a

more pleasing design to the eye, nevertheless such legs are not necessary, since the cylindrical shapes of the spring members lend themselves as suitable supports for the device with either face uppermost and therefore the invention is not limited in this respect.

The pinch levers 8 are pierced as at 11, in order to afford a good grasp on the levers 10 and also to provide convenient means for hanging the device up when not in use.

What is claimed is:—

1. A device of the character set forth, comprising cylindrical spring members having resilient edges facing inwardly and having openings in their outer walls and slots on opposite sides of said openings, an abradant carrying plate positioned between said edges and having lugs extending through said openings and bent, clamps confined between said plate and edges and having diverging pinch levers extending through said slots, and wipers confined be-

tween said edges and clamps and projecting inwardly beyond said clamps. 25

2. A pencil sharpener and wiper, comprising cylindrical end springs having resilient edges facing each other, an abradant carrying support secured at its ends to the outer walls of said springs and extending between said edges, clamping members confined between said support and edges and having diverging pinch levers that extend through said walls, and felt wipers extending inwardly beyond said clamps and confined between the latter and said edges. 35

3. A construction as in claim 1 in which the lateral ends of the abradant carrying plate are formed with pairs of ears, the ears of each pair being bent at right angles to the plate and in opposite directions to constitute legs. 40

In testimony whereof I affix my signature hereto.

WARREN R. BRIGGS.
